2,425,660

METHOD AND APPARATUS FOR MAKING
PAPER-COVERED VENEER

Richard N. Ware, Jr., and Reginald Cannon,
Tallulah, La., assignors to Chicago Mill and
Lumber Company, Chicago, Ill., a corporation
of Delaware

Application September 19, 1945, Serial No. 617,244

8 Claims. (Cl. 154—138)

1

This invention relates to the production of paper covered wood veneer from green, undried wood and moistened paper.

Specifically this invention relates to a continuous process and continuously operating apparatus for producing paper covered wood veneer. The process of the invention requires only one drying operation and produces a laminated product free from wrinkles and blisters.

In accordance with this invention, green, undried lumber is peeled from a log by a rotary cutting lathe. Such lumber may contain varying amounts of moisture, depending upon its density, the locality in which it is found, etc. Lumber found in Madison Parish, Louisiana, for example, averages about 130% moisture content. This means that moisture is present in the lumber at the ratio of 130 pounds of water to 100 pounds of dry wood fiber. The veneer is selectively fed to superimposed belts or conveyors. Some of these conveyors supply short lengths of veneers to a trimming machine where imperfect wood sections are eliminated. The trimmed sheets are then stapled together and are fed back to one of the superimposed conveyors to be used as needed. The other conveyors supply longer lengths of veneer through a trimming machine where imperfect sections are removed. The veneer pieces are then fed through a stapler to be connected together to form a continuous ribbon. As the pieced-together sheets from the aforementioned conveyor are needed, they can be fed down to the next lower conveyor and are connected to previously fed sheets to form a continuous ribbon. The continuous ribbon is then fed by a conveyor between the adhesive coated faces of paper sheets. These paper sheets have previously been moistened by wetting rolls and tensioned. The non-moistened faces of the paper are then coated with adhesive such as, for example, a soy bean glue in water solution or suspension. The moistened, adhesive-coated paper sheets are next pressed onto opposite faces of the wood veneer ribbon and are adhesively united to the wood veneer by means of a series of pressure rolls. The moistened glue coated sheets have a moisture content balancing the moisture content of the wood. For example, when the wood has a moisture content of 130%, the glue on the paper is regulated to put 120% of moisture into the two paper sheets and the wetting rolls bring the moisture content of the two sheets up to 130% to balance the moisture content of the wood. The continuous ribbon of paper covered wood veneer is then passed through a clipping machine to be

2

severed into desired lengths. The severed lengths are selectively fed to superimposed conveyors passing through a drier or kiln. The drier or kiln is equipped with a heated air circulating system to dry the paper covered veneer and set the adhesive. The drier is preferably operated at an inlet temperature of 250° F. and an outlet temperature of 350° F.

The laminated paper covered veneer entering the drier contains about 100 to 106% moisture by weight, and the moisture content of the paper covered veneer is reduced to about 20 to 30% by weight before the paper covered veneer is heated up to 160° F. The paper covered veneer, however, is further dried before leaving the drier to have a moisture content of about from 6 to 12% by weight, thereby equaling the normal humidity conditions of the atmosphere, and preventing warping of the product.

20 A feature of the invention resides in the provision of a continuous process wherein wood veneer sheets are secured in end to end relation to form a continuous ribbon, and wherein continuous sheets of paper are adhesively united to one or both faces of the continuous ribbon of veneer.

25 Another feature of the invention resides in the elimination of heretofore-required pre-drying steps; and the utilization of wet or green wood together with moistened paper to form a laminated paper covered veneer with only one drying operation for both the wood and the paper.

30 A further feature of the invention resides in the moistening of paper prior to its application to the wood for eliminating formation of bulges and wrinkles in the paper when the wood shrinks upon drying. The moistened paper is expanded and shrinks with the wood so that the product has smooth, flat paper faces.

35 An object of the invention is to provide a continuous process of producing paper covered veneer.

40 A further object of the invention is to provide a process of covering wood veneer with paper which process requires only a single drying operation and utilizes undried wood.

45 Another object of the invention is to provide a continuous process of making paper covered veneer wherein wood veneer sheets are secured in end to end relation to form a continuous ribbon and are then covered with moistened, adhesive-coated paper, subjected to pressure treatment to form a laminated assembly, then cut into desired lengths, and next dried to form a smooth faced product.

50 A further object of the invention is to eliminate

the formation of wrinkles, blisters and bulges on paper covered veneer by creating, in the paper, moisture conditions simulating those in the wood so that the paper and wood will simultaneously shrink upon being dried.

A further object of the invention is to provide apparatus for forming paper covered veneer in a continuous manner.

A further object of the invention is to provide apparatus for forming paper covered wood sheets, which apparatus produces a continuous ribbon of wood veneer, covers one or both faces of the continuous ribbon with paper, severs the paper covered ribbon into the desired lengths, and dries the lengths.

Other and further objects of the invention will become apparent to those skilled in the art from the following detailed description of the annexed sheets of drawings which, by way of a preferred example only, illustrates one type of apparatus according to this invention, for carrying out the process of this invention, and further illustrates the product of this process and apparatus compared with prior known products.

On the drawings:

Figure 1 is a fragmentary broken diagrammatic side elevational view of the first portion of the apparatus of this invention which portion produces a continuous wood veneer ribbon.

Figure 2 is a view similar to Figure 1 but illustrating the second portion of the apparatus which portion covers the wood veneer ribbon with moistened adhesive coated paper and presses the paper onto the ribbon.

Figure 3 is a view similar to Figures 1 and 2 but illustrating the third or last portion of the apparatus which portion severs the paper covered veneer ribbon into sheets of the desired lengths and dries the sheets.

Figure 4 is a plan view, with parts broken away to illustrate the underlying wood, of a heretofore known paper covered wood veneer sheet.

Figure 5 is a side elevational view taken along the line V—V of Figure 4.

Figure 6 is a view similar to Figure 4 but illustrating the product of this invention.

Figure 7 is a side elevational view taken along the line VII—VII of Figure 6.

As shown on the drawings:

In Figure 1 the reference numeral 10 designates a rotary log peeling lathe commonly used in cutting veneers. The lathe 10 includes a rotating driving support 11 and a blade 12. A log 13 is mounted on the support 11 to be driven in the direction shown by the arrow and the blade 12 cuts a veneer sheet 14 from the log 13. A conveyor 15 in the form of an endless belt trained around rollers feeds the veneer sheet 14 to a tipple 16 which as illustrated can be tilted to selectively feed the veneer to any one of six superimposed conveyors 17, 18, 19, 20, 21 and 22. These conveyors are in the form of greatly elongated belts trained around rollers and receiving the veneers on the upper runs thereof. The bottom conveyor 17 supplies the veneer thereon to a conveyor 23 feeding a cutter or trimmer 24 which cuts out imperfect veneer sections and supplies a stapling machine 25 with trimmed veneer sheets. The trimmed sheets are united by the stapler 25 to form a continuous ribbon of wood veneer which is received on a conveyor 26.

The second conveyor 18 also supplies the conveyor 23 and the veneer from the conveyor 18 can

slide down an inclined guide 27 onto the conveyor 23.

The third conveyor 19 is driven in a direction opposite to the direction of the conveyors 17 and 18 for a purpose to be more fully described.

The top three conveyors 20, 21 and 22 supply veneer sheets to an inclined conveyor 28. Guides 29 and 30 respectively guide the veneer from the conveyors 22 and 21 to the conveyor 28. A conveyor 31 receives the veneers from the conveyor 28 to direct the same through a cutter 32. A stapler 33 secures the cut veneers together into a continuous ribbon and this ribbon is allowed to drop onto a conveyor 34 feeding the conveyor 19.

In operation, short veneers or imperfect veneers are fed to the top conveyors 20, 21 and 22 for being trimmed and united into a longer ribbon of veneer. This longer ribbon of veneer is fed, as needed, by the conveyor 19 to the conveyor 18 where it is joined with a ribbon on the conveyor 23 to form a continuous ribbon. The superimposed conveyors 17 to 22 can thus be operated to store veneer sheets until needed while the upper trimmer and staplers 32 and 33 are utilized to supply longer ribbons for connecting with ribbons passing through the lower trimmer and staplers 24 and 25. A continuous ribbon of wood veneer is thus received by the conveyor 26.

The conveyor 26 supplies the continuous veneer ribbon to an inclined conveyor 35 which, as shown in Figure 2, feeds a horizontal conveyor 36.

The second section of the machine shown in Figure 2 is for the purpose of covering the veneer ribbon with adhesive coated moistened paper and for pressing the paper onto both faces of the ribbon.

As shown in Figure 2, a roll of paper 37 supplies the web W over a fountain roll 38 rotatably mounted in a tank 39 containing a pond P of water. A heating coil 40 heats the water to keep its temperature around 180° F. The fountain roll 38 picks up a film of water from the pond P and deposits the film onto the underface of the web thereby moistening the web. Tension rolls 41 and 42 are provided on opposite sides of the fountain roll 38 to hold the web in a taut condition as it passes around a portion of the periphery of the roll 38. The moistened web is then directed over a guide roll 43 and under another guide roll 44 to pass under a driven coating roll 45. The coating roll is positively driven in the direction shown by the arrow and supplies a flowable liquid adhesive from a trough T in amounts determined by an inking roller 46, to the top face of the moistened web. The film of coating material is regulated by pressure in the nip between the coating roll and inking roll. The coating roll 45 pulls and stretches the wet web. The coated paper is then trained around a turning roll 47 to pass over the top of the veneer ribbon from the conveyor 36 and presents its coated face to the veneer.

As shown in dotted lines a second roll of paper 37' is provided adjacent the roll 37 to supply the fountain roll 38 when the roll 37 is exhausted. The leading edge of the new roll is secured to the trailing edge of the exhausted roll so that the continuous process will not be interrupted.

A second roll of paper 48 is rotatably supported at a level beneath the veneer fed by the conveyor 36. This second roll supplies a web W' over a guide roll 49 to a turning roll 50 which reverses the direction of travel of the web and feeds the web over a second fountain roll 51 rotating in a pond P' of water contained in a

tank 52 and heated by means of a heating coil 53 in the same manner described above. A tension roll 54 cooperates with the roll 48 but on the opposite side of the fountain roll 51 to hold the paper in a taut condition as it passes around the fountain roll 51. The moistened paper travels around guide rolls 55 and 56, under a guide roll 57 and over another guide roll 58 to a positively driven coating roll 59 which is rotated in the direction shown by the arrows to pull and stretch the water wet web. An inking roll 60 cooperates with the coating roll 59 to hold a trough T' of the same coating material maintained in the trough T. A film of coating material is deposited on the coating roll 59 and transferred to the under face of the moistened web W'. The coated web W' then passes around a turning roll 61 and is directed under the veneer ribbon fed by the conveyor 36.

The water added to the webs W and W' by the moistening rolls and by the glue is regulated to balance the moisture content of the veneer. Thus if the wood has a moisture content of 130 pounds of water per 100 pounds of dry fiber the two wet glue coated webs W and W' will have a water content of 130 pounds of water per 100 pounds of dry fibers in the two webs or 65 pounds of water per 100 pounds of dry fiber in each web W or W'. If the wood is covered with one web only, then the water content of this single web should balance the water content of the wood.

The coated faces of the two moistened webs W and W' are pressed onto the opposite top and bottom faces of the veneer ribbon 14 as the assembly passes between the first pair of squeeze rolls 62. The paper covered veneer then passes between a series of press rolls 63. These press rolls are of smaller diameter than the first press rolls 62 and are preferably set so as to exert increasing pressures on the laminated assembly. After passing between the last pair of small diameter press rolls, the assembly then passes between three pairs of positively driven larger diameter press rolls 64 as shown in Figures 2 and 3. These press rolls 64 and the coating rolls 45 and 59 are the only positively driven rolls in the second section of the apparatus and serve to feed the paper to the wood veneer ribbon as well as to pull the paper covered assembly through the presses.

An auxiliary roll of paper 48' is provided adjacent the roll 48 to supply paper to the fountain roll 51 when the roll 48 is exhausted and thereby maintains continuous operation for the apparatus.

The paper coated assembly from the last press roll 64 is fed through a cutter 65 as shown in Figure 3 to be cut into sheets of the desired length, and these sheets are deposited on a tipple 66 which selectively supplies four superimposed conveyors 67, 68, 69 and 70. These conveyors extend through a drier or kiln 71 and have runs of appreciable length in advance of the inlet of the kiln as well as extending beyond the outlet of the kiln. A blower 72 is mounted on top of the kiln 71 and has an inlet duct 73 communicating with the inlet end of the kiln. A duct 74 extends along the top of the kiln from the outlet of the blower 72 and supplies a feed duct 75 communicating with the kiln near the outlet end thereof. The air and kiln are heated by steampipes or the like (not shown) so that an inlet temperature of around 250° F. and an outlet temperature around 350° F. is maintained. The circulating air and heat in the kiln drives the moisture out of the paper and wood to produce a dried product containing enough mois-

ture so that it will not warp when exposed to the atmosphere. The length of the run of the conveyor beyond the outlet end of the kiln is sufficient so that the product will cool down to a temperature convenient for handling. The product is removed from the conveyors and stacked or packaged. No further treatment of the product is necessary.

The entire apparatus is operated to continuously move the material therethrough at the rate of from 20 to 60 linear feet per minute.

As shown in Figures 4 and 5 attempts to adhesively unite paper with undried or green veneer has, prior to this invention, resulted in the production of products having wrinkled, blistered and uneven paper covers. In Figures 4 and 5 the reference numerals 76 represent a sheet of wood veneer covered on both broad faces by paper sheets 77. These paper sheets 77 have wrinkles and uneven undulations 77a therein extending transversely across the grain of the wood. These wrinkles are caused by shrinkage of the wood upon drying. Since green undried lumber shrinks appreciably across the grain thereof when the wood is dried, and since paper secured thereon does not shrink to the same extent, the shrinkage of the wood will pucker and wrinkle the paper as shown.

The product of this invention, on the other hand, has smooth, unwrinkled paper faces as shown in Figures 6 and 7 wherein the reference numerals 78 designate the wood veneer sheet and the reference numerals 79 designate the paper covers on the veneer sheet. The moistening of the paper according to this invention causes the same to expand. The expanded paper is adhesively united, in its expanded condition, to the green undried wood. When the wood veneer is dried, the moistened paper is also dried and shrinks at the same rate as the wood. The grain of the wood extends substantially transversely across the width of the veneer ribbon. The paper on the other hand preferably has the fibers extending longitudinally along the length of the sheet of paper. These fibers tend to expand when moistened and shrink when dried. Since the wood, when moistened, expands mainly across the grain thereof, cross-grain shrinkage of the wood is about the same as along-the-grain shrinkage of the paper. A smooth paper faced product is thus produced.

From the above description it shall be understood that this invention provides a continuous process of making paper faced wood veneer wherein wood veneer sheets are cut from green undried logs and are united in end to end relation to form a continuous veneer ribbon. The veneer ribbon is covered on one or both faces with expanded moistened paper having the grain thereof in substantially right angular relation to the grain of the veneer ribbon. The paper is moistened on the face thereof that is to form the outer surface of the product. The moistened paper is held taut and expands or stretches before being contacted with the veneer ribbon. The other face of the paper is coated, immediately prior to being contacted with the veneer ribbon, with a water solution or suspension of an adhesive that sets on drying. A soy bean glue adhesive is especially satisfactory. The water content of the paper is regulated to balance the water content of the wood. Thus if two sheets of paper are used, to cover opposite faces of the wood, each sheet will have one-half the moisture content of the wood while if one sheet is used to cover only

one face of the veneer, this sheet will have substantially the same moisture content as the wood. The adhesive coated face of the paper is pressed onto one or both faces of the veneer ribbon, the paper covered veneer ribbon is cut into segments of the desired length, and the segments are dried to simultaneously dry the paper and wood thereby causing the same to shrink uniformly and produce a smooth faced paper covered veneer wood product. Only one drying operation is necessary and the entire process is continuous with the material moving along at a rapid rate.

We claim as our invention:

1. The continuous method of forming paper covered veneer which comprises uniting undried green veneer sheets in end to end relation to form a continuous veneer ribbon, wetting one face of a web of paper with heated water, stretching the wet paper, coating the other face of the wet paper with an adhesive, continuously advancing the ribbon of veneer and the coated wet paper, pressing the coated face of the wet paper against a face of the veneer while simultaneously advancing the veneer ribbon and paper, cutting the veneer ribbon with the paper thereon into sheets of the desired lengths, and drying the paper covered sheets to simultaneously dry the wood, the paper and the adhesive for producing paper covered veneer sheets having smooth flat paper surfaces.

2. In the method of making paper covered veneer the steps which comprise forming a continuous ribbon of undried veneer wood, wetting a continuous web of paper with water, stretching the wet paper, coating one face of the wet paper with an adhesive, continuously advancing the ribbon of veneer and the coated wet paper in the same direction, pressing the coated face of the paper against the veneer ribbon, repeating the pressing operation at spaced intervals along the length of travel of the veneer ribbon and paper until the paper is adhesively united to the veneer ribbon, and drying the paper covered veneer to simultaneously drive out moisture from the paper, wood, and adhesive and thereby cause the wood and paper to shrink at the same rate for producing a smooth paper face on the veneer.

3. In the continuous method of forming paper covered veneer wood the steps which comprise peeling a green undried log to cut veneer sheets therefrom, conveying the veneer sheets selectively to superimposed conveyors, depositing the shorter veneer sheets on the upper conveyors, trimming defective areas from the short veneer sheets, joining the trimmed short veneer sheets into an elongated ribbon, depositing the longer veneer sheets from the log on the lower conveyors, trimming defective areas from the longer veneer sheets, securing the trimmed longer sheets together to form an elongated veneer ribbon, connecting the elongated veneer ribbon from the lower conveyors with the connected elongated ribbon from the upper conveyors to form a continuous elongated ribbon, advancing the continuous elongated ribbon in a substantially horizontal plane, unreeling paper sheets from rolls of paper above and below the advancing elongated ribbon, depositing films of heated water on one face only of each unreeled web of paper, pulling the paper over coating rolls to stretch and expand the wet paper, depositing a film of adhesive from the coating rolls onto the face of the paper opposite the wet face, pressing the adhesive coated faces of the paper against the top and bottom faces of the veneer ribbon, simultaneously advancing the pressed together paper and veneer ribbon, sub-

jecting the paper and veneer ribbon to a series of spaced pressing operations at room temperatures to adhesively unite the paper to the veneer ribbon, passing the paper covered veneer ribbon through a heating tunnel, circulating heated air through the heating tunnel to maintain a tunnel inlet temperature around 250° F. and a tunnel outlet temperature around 350° F., and drying the paper covered veneer in said heating tunnel from an initial moisture content of about 100 to 106% moisture to a moisture content of around 6 to 12% to thereby produce paper covered veneer having smooth flat paper faces.

4. Apparatus for continuously producing paper covered veneer which comprises a rotary veneer cutter, a tipple receiving veneer from said cutter, a plurality of superimposed conveyors receiving veneer from said tipple, superimposed cutting machines at the ends of said conveyors, superimposed stapling machines adjacent said cutting machines, a conveyor for transferring veneer from the upper tiers of said superimposed conveyors through the top cutter and stapling machines, a conveyor for transferring veneer from the upper stapling machine to a lower conveyor, a conveyor for transferring veneers from the lower tiers of said superimposed conveyors through the lower cutter and stapling machines, a series of driven press rolls spaced longitudinally from the lower stapling machine to pull the veneer ribbon along a horizontal plane, means for supporting rolls of paper above and below the veneer ribbon, machines for wetting paper from said rolls, coating machines for coating said paper, guide rolls for directing the coated paper into contact with the top and bottom faces of the veneer, a plurality of press rolls in advance of said positively driven press rolls, and a drier tunnel receiving paper-covered veneer from said press rolls.

5. The method of making paper covered veneer which comprises forming a ribbon of undried green wood veneer, wetting two webs of paper with water, stretching the wet webs, coating one face of each of the two wet paper webs with a wet glue, regulating the water content of each coated wet web to produce in the two webs a total moisture content substantially equaling the moisture content of the wood veneer ribbon, depositing the coated faces of the wet paper webs on opposite faces of the wood veneer ribbon, pressing the paper webs against said faces, and drying the resulting laminated assembly.

6. A method of making paper covered veneer which comprises forming a ribbon of undried wood veneer, wetting one face of each of two webs of paper, coating with a wet glue the faces of said webs opposite the wet faces thereof, stretching the wet webs, depositing the glue coated faces of the wet webs on opposite faces of said wood veneer ribbon, pressing the webs against the veneer ribbon, and simultaneously drying the wood, the paper, and the adhesive to thereby cause the wood and paper to shrink simultaneously and produce a laminated paper covered wood veneer with smooth paper faces.

7. The method of making paper covered veneer which comprises forming a ribbon of wet veneer wood, wetting one face of a web of paper with water, coating the other face of the paper with a water containing glue, stretching the wet paper, continuously advancing the ribbon of veneer and the coated wet paper in the same direction, pressing the coated face of the paper against the veneer ribbon, and drying the paper covered

veneer to simultaneously drive out moisture from the paper, the wood, and the adhesive to thereby cause the wood and paper to shrink at the same rate for producing a smooth paper face on the veneer.

8. Apparatus for continuously forming paper covered veneer which comprises cutting machinery for forming a veneer ribbon from logs, apparatus for uniting succeeding veneer ribbons in end to end relation to form a continuous ribbon, a series of ribbon press rolls arranged for pulling the veneer ribbon therebetween along a horizontal plane, means for supporting rolls of paper above and below the veneer ribbon, machines for wetting one face of each sheet of paper from said rolls of paper, coating machines for coating the other face of each sheet of paper, means for stretching the wet sheets of paper, guide rolls for directing the coated wet stretched paper into contact with the top and bottom faces of the veneer 20

ribbon to place the coated faces of the paper against the faces of the wood, and means for simultaneously drying the wood, the glue, and the paper to produce paper covered veneer having 5 smooth flat paper surfaces.
